UNITED STATES PATENT OFFICE.

JOHN G. LANNING, OF DETROIT, MICHIGAN, ASSIGNOR TO DETROIT LUBRICATOR COMPANY, OF DETROIT, MICHIGAN, A CORPORATION OF MICHIGAN.

FUELIZER.

Application filed January 15, 1921. Serial No. 437,540.

To all whom it may concern:

Be it known that I, JOHN G. LANNING, a citizen of the United States of America, residing at Detroit, in the county of Wayne and State of Michigan, have invented certain new and useful Improvements in Fuelizers, of which the following is a specification, reference being had therein to the accompanying drawings.

10 The invention relates to fuelizers and consists in certain novel features of construction as hereinafter set forth.

In the drawings:

15 Figure 1 is a cross-section through the fuelizer;

Figure 2 is a longitudinal section therethrough;

Figure 3 is a horizontal section.

20 In the construction shown the fuelizer is formed as a unit which is insertable between the carburetor and the inlet manifold of an internal combustion engine, said unit comprising a casing A having therein a conduit section B, which forms a portion of the intake with a chamber surrounding said conduit section and an outer jacket D surrounding said chamber. The combustible mixture is drawn into the fuelizer from the carburetor and as shown is first drawn through a 25 hollow throttle valve E, passing through the hollow stem F thereof into a port G which is in registration with a port H in the fuelizer in the chamber formed by the outer jacket thereof. From this chamber the combustible mixture passes around the jacket and through a valve controlled port I into the chamber C, where it is ignited by a spark plug J and the flame and products of combustion pass around the conduit section 30 B and finally, after the extinguishing of the flame, into the intake.

With the construction as thus far described, it is vital that the flame be completely extinguished before passage into the intake, as otherwise it will explode the mixture therein. I have therefore provided a construction which effectually guards against any passage of the flame and which is as follows: K is a screw-threaded plug 45 which engages a correspondingly threaded opening through the outer and inner jackets communicating with the chamber C. In alignment with this aperture there is an aperture L in the wall of the conduit section B, through which the products of combus-

tion enter the intake. M and N are outer and inner concentric tubes which are secured at one end to the plug K and extend inward therefrom to the conduit section B. The inner tube N is threaded at its inner end for engagement with the aperture L, which is correspondingly threaded, and the arrangement is such that by screwing in the plug K engagement is also made between the inner tube N and the wall of the conduit B. The 50 inner tube is further provided near its upper end with a plurality of apertures N' for establishing communication between its interior and the space within the outer tube M, while the latter tube is provided at its opposite or inner end with a plurality of apertures M', establishing communication between the chamber C and the space between the tubes. Thus the suction of the intake will draw the flame and products of combustion from the chamber C, first 55 through the apertures M' into the space between the tubes and then through the apertures N' into the inner tube and into the intake. In passing through these apertures the temperature is lowered and as the inner tube is shielded from direct contact with the flame in the chamber C, it will be at 60 sufficiently low temperature to insure the extinguishing of any flame which passes through the apertures in the outer tube before it can pass through the apertures in the inner tube. It will also be noted that as both inner and outer tubes are attached to the plug K, the heat will be rapidly conducted outward, while the unignited combustible mixture in the outer jacket contacting with said plug will have a cooling effect thereon. As a further safeguard, there 65 is arranged within the chamber C a baffle O which passes up to about the longitudinal center of the tubes M and N and then across, being apertured for the passage of said tubes. This will compel the flame in the chamber C to pass around in the direction indicated by the arrows and will further lower the temperature before the gaseous products reach the intake.

When a fuelizer is used in cold weather, 70 there is always a certain amount of condensation in the outer jacket, due to the contact of the liquid fuel with the outer cold walls. This condensation will drop to the lower portion of the passage when the fuelizer is not in use and if it is subsequently 75

thrown into operation, the quantity of liquid fuel in the passage will form an over-rich mixture, interfering with the ignition of the same. I have therefore provided means for removing the condensation from the outer passage and introducing it into the chamber C at a point beyond the ignition point. Here its presence is unobjectionable as the only effect that it can have is to extinguish the flame which necessarily must occur before entrance into the intake. As specifically shown, the lower portion of the fuelizer is tapered and at its lower end is an aperture normally closed by a plug P. This plug has a well or sump P', which forms the lowermost point in the outer passage. Q is a second plug engaging an aperture in the wall separating the outer passage from the inner chamber C and this plug has a restricted aperture Q' therethrough and through a downward extension Q² of the plug into the well or sump P'. With this construction there will always be a higher vacuum in the inner chamber C than in the outer passage, and consequently, any liquid fuel which collects in the sump P' will be drawn up through the passage Q' and into the bottom of the chamber C. Here it will be in the path of the flame ignited by the spark plug J and will be swept along with the flame and products of combustion passing finally into the intake. For thermostatically controlling the operation of the fuelizer, the port I is controlled by a sleeve valve R, which in turn is actuated by a thermostat S. This construction does not, however, form any part of the present invention.

What I claim as my invention is:

- 40 1. In a fuelizer, the combination with a casing having a conduit section therethrough forming a portion of the engine intake, and a surrounding chamber constituting a combustion chamber, of means for preventing passage of flame from said combustion chamber into said intake comprising concentric inner and outer tubes having perforations therein out of registration with each other, the outer tube forming a shield for the inner tube, and means for conducting away the heat from the inner tube.
- 45 2. In a fuelizer, the combination with a casing having a conduit section therethrough forming a portion of the engine intake, and a surrounding chamber constituting a combustion chamber, of means for preventing the passage of flame from said combustion chamber into said intake comprising a plug engaging an aperture through the outer wall
- 50 3. of the casing, concentric tubes secured to said plug and extending inward therefrom, the inner tube engaging an aperture in the wall of the intake, said tubes having perforations therein out of registration and at
- 55 4. opposite ends thereof, whereby the products

of combustion passing through the outer tube must pass through apertures in a portion of the inner tube shielded by said outer tube.

3. In a fuelizer, the combination with a 70 casing having a conduit section therethrough forming a portion of the engine intake and a surrounding chamber constituting a combustion chamber, of means for preventing the passage of flame from said combustion chamber into said intake, comprising a plug 75 engaging an aperture in the outer wall of the casing, concentric tubes carried by said plug, the inner tube engaging an aperture in the wall of the intake and said tubes having perforations therein out of registration and at opposite ends thereof, and a baffle for protecting the perforated portion of the outer tube from direct impingement of the flame, said inner tube being protected by 80 said outer tube.

4. In a fuelizer, the combination with a 90 casing having a conduit section therethrough forming a portion of the engine intake and a surrounding chamber constituting a combustion chamber, and a jacket surrounding said combustion chamber forming a passage for the entrance of combustible mixture thereto, means for preventing the passage of 95 flame from said combustion chamber into said intake, comprising a plug for engaging registering apertures in said outer jacket and outer wall of the combustion chamber, outer and inner tubes carried by said plug extending through said combustion chamber, the inner tube engaging an aperture in the wall of the intake, said outer tube having perforations through its inner end portion, and said inner tube having perforations through its outer end portion, and said plug passing through the outer passage for the combustible mixture, whereby it will be 100 cooled.

5. In a fuelizer, the combination with a 110 casing having a conduit section therethrough forming a portion of the engine intake, and a surrounding chamber constituting a combustion chamber, of means within the combustion chamber for preventing passage of the flame from said combustion chamber into said intake comprising spaced telescopically arranged and outer tubes having perforations therein out of registration with each other, one of said tubes being in communication with the conduit section of said 115 casing.

6. In a fuelizer, the combination with a 120 casing having a conduit section therethrough forming a portion of the engine intake, a surrounding chamber forming a combustion chamber, a chamber surrounding the combustion chamber and cooperating therewith to form a passage for combustible mixture to said chamber, and a connection between 125 said passage and said combustion chamber 130

for automatically removing the condensation of liquid fuel.

7. The combination with an intake conduit of an internal combustion engine, of a fuelizer including a casing having a conduit section in communication with the intake conduit, a combustion chamber surrounding the conduit section and in com-

munication therewith, a passage in communication with the intake conduit for supplying liquid fuel to said combustion chamber, and a connection between said passage and said combustion chamber for automatically removing the condensation of liquid fuel. 10

In testimony whereof I affix my signature.
JOHN G. LANNING.
